COIN BOX FOR COIN-OPERATED APPLIANCES

Marlyn R. Hutchins, Minneapolis, Minn., assignor to
Coin Security Systems, Inc., Minneapolis, Minn.,
a corporation of Minnesota

Filed Nov. 23, 1966, Ser. No. 4,787

Term of patent 14 years

(Cl. D52—3)

FIG. 1 is a front perspective view of a coin box for coin-operated appliances, showing my new design;

FIG. 2 is a side elevational view thereof;

FIG. 3 is a top plan view thereof;

FIG. 4 is a rear elevational view thereof; and

FIG. 5 is a front elevational view thereof.

The dominant features of the design reside in the portions shown in full lines.

I claim:

The ornamental design for a coin box for coin-operated appliances, as shown and described.
